MEANS FOR CONNECTING SHEETS OF A
NEWSPAPERHenry A. Wise Wood, New York, N. Y., assignor
to Wood Newspaper Machinery Corporation,
New York, N. Y., a corporation of VirginiaApplication December 1, 1934, Serial No. 755,541
Renewed July 13, 1937

9 Claims. (Cl. 270—37)

The principal objects of this invention are to provide a simple means for securing the different sheets in a newspaper or similar product without paste and at high linear web speeds; to provide means for interlocking the sheets as they are brought down over the former without reduction in the speed of the web, and to provide means for accomplishing this result which has none of the disadvantages encountered with the use of glue fountains.

Other objects and advantages of the invention will appear hereinafter.

Reference is to be had to the accompanying drawings, in which

Fig. 1 is a front view of a former for a printing press with a preferred embodiment of this invention applied thereto;

Fig. 2 is a side elevation of the same, partly in section;

Fig. 3 is an enlarged cross sectional view of the punching arrangement;

Fig. 4 is a similar view on still further enlarged scale showing the manner in which the interlocking flaps are turned under to anchor the sheets securely together;

Fig. 5 is a flat view showing the preferred location of the interlocking means on a newspaper;

Fig. 6 is a view of the interlocked web coming down through the former rolls and illustrating a modification, and

Fig. 7 is a similar view showing another modification.

It was customary at one time to paste the sheets of a newspaper together to form it into a kind of book. However, more recently the popularity of tabloid papers and the increasing speed at which presses have been run have practically necessitated the discontinuation of that practice.

No method or machine has been devised to paste the sheets properly at the high linear speeds now in vogue and in a simple manner. Such interlocking means is particularly desirable in papers comprising a single or "dinky" sheet. It is, of course, disadvantageous to use glue fountains for pasting the sheets together. This invention is designed to secure the desired results without their use, in a simple manner and in a way in which it can be operated at high web speed.

In the form illustrated a former support 1 is mounted in the usual way in the frame 2 of the folder. The support carries secured thereto a bracket 3 which pivotally supports the former 4 by a shaft 5. The lower end of the former 4 is pivotally secured in position to an eye bolt 7 by

a stud 6. The right hand end of the eye bolt in Fig. 2 penetrates a hole in the former support held in position by nuts 8 on opposite sides of a flange of the support. The nose 9 of the former is secured to the former 4 and pivotally carries a former tip 10 of standard construction. Of course, a drag roll 11 is used as a means for leading the web to the former.

The usual former rolls 12 and nipping rolls 13 are shown for guiding the sheet down to the folding and delivering mechanism, not shown. The nipping rolls 13, as usual, are driven from some part of the press through a shaft 14 and suitable gearing.

The former 4 is provided with an opening 15 extending through it and located along its center line. Above this opening is located a punching roller 16 substantially tangent to the line of the web and a die roller 17 extends through the opening substantially in contact with the back of the web. These rollers are mounted on shafts 18 and 19 respectively. The punching roller 16 carries projections 20 which register with complementary depressions 21 in the die roller 17.

As the webs W and W' are led between these rollers the projections will punch out a small flap 22 from all the webs which may be passing through this mechanism as the webs pass over the former. These flaps will be located near the center of the web. As the webs progress further down the former the flap 22 comes in contact with an edge 23 carried by the former at the lower side of the opening 15. The travel of the webs past this edge tends to fold the flap in a backward direction, as shown in Fig. 4, under the lower web.

It will be obvious that not only does the punching of the flap 22 in itself serve to interlock the webs but when the flap is folded back, as stated, a very secure hold is obtained between the several webs.

The drive for the punch and die rolls may be accomplished through sprockets 24 and 25 respectively on the shaft 14. These sprockets carry chains 26 and 27, one of them to drive the shaft 18 directly on which the punch roll is mounted. The other chain 27 drives a jack shaft 28 which, through bevel gear 29 and 30, rotates a shaft 31.

To the other end of this shaft 31 is secured a bevel gear 32 driving a bevel gear 33 secured to the shaft 19 and therefore driving it. Obviously, the shafts 18 and 19 may be driven in such ratios that the projections on the punch roll 16 cooperate with the die roll 17 to cut out the flap, as previously described.

The rolls 16 and 17 are shown as of the same diameter so that they are driven at the same speed but, if they were of different diameters, they would be driven at a proportionate speed ratio.

In Figs. 1 and 5 are shown two lines of flaps 22 staggered longitudinally of the web and placed on opposite sides of the central longitudinal fold.

Fig. 6 is a modification in which the flaps are placed on one side of the longitudinal fold. The object of this is to get the flaps located on the back sheet of a folded newspaper. This is a desirable arrangement because, in this manner, a better front page appearance is presented.

Fig. 7 shows still another modification where the flaps 22 are placed directly in the center line of the fold. This permits the pages to be hinged in the exact center.

In this way the different webs, and therefore the different sheets after they are cut up into a newspaper, are interlocked without the use of glue and in such a manner that the folder can be operated at full linear speed. At the same time the method of producing the interlocking is reduced to its simplest elements. The invention can be applied to full or single sheets, as stated.

Having thus described my invention and the advantages thereof, I do not wish to be limited to the details herein disclosed, otherwise than as set forth in the claims, but what I claim is:—

1. In a machine for connecting the sheets of a newspaper, the combination of means for directing a plurality of webs over a course, and means for projecting a small portion of one web entirely through another web while the webs are traveling.

2. In a machine for connecting together two sheets of a newspaper, the combination of means for directing two webs to travel over a course, and rotary means for projecting a small portion of one web through to the back of another web while the webs are traveling at full speed.

3. In a machine for connecting the sheets of a newspaper, the combination with a folder and means for feeding a plurality of webs over the folder, of means for projecting part of one web all the way through another web to connect them while the webs are running over the folder.

4. The combination with a folder having a former for conducting a plurality of webs, of a pair of rollers in position to engage the webs on opposite sides and having means for punching holes through the webs and the former having an opening provided with an edge in position for

forcing a flap from one web through the other, for the purpose described.

5. The combination with a former for conducting a plurality of webs to a folding machine, said former having an opening therethrough, a pair of rollers, one projecting into the opening, one of said rollers having a series of punches around its circumference and the other having a series of registering depressions into which the punches are adapted to force, in each case, a small piece 10 of the webs, the opening in the former having an edge adapted to engage these projecting pieces of paper as the webs pass over the former and bend them back against the bottom web, for the purpose described. 18

6. The combination with a former for conducting a plurality of webs to a folding machine, a pair of rollers, said rollers being adapted to engage the opposite sides of a plurality of webs movable over the former, means for rotating said rollers, one of said rollers having a series of punches around its circumference and the other having a series of registering depressions into which the punches are adapted to force, in each case, a small piece 20 of the web nearest the punching rollers 23 through the webs behind it, and an opening in the former having an edge adapted to engage these projecting pieces of paper as the webs pass over the former and bend them back against the bottom web. 30

7. In a machine for connecting the sheets of a newspaper, the combination of means for punching openings through a plurality of webs along one side of the center of the line of the central longitudinal fold which is made to convert the 35 web into a newspaper and projecting a portion of one web entirely through an opening in another web.

8. In a machine for connecting the sheets of a newspaper, the combination of means for punching openings through a plurality of webs along the center of the line of the central longitudinal fold which is made to convert the web into a newspaper and projecting a portion of one web entirely through an opening in another web. 40

9. In a machine for connecting the sheets of a newspaper, the combination of means for punching flaps through a plurality of webs, said flaps being staggered longitudinally of the web and placed on opposite sides of the central longitudinal fold which is made to convert the web into a newspaper. 45 50
